(57) **CLAIM**

The ornamental design for a tool for holding fish, as shown.

DESCRIPTION

FIG. 1 is a perspective view of the tool for holding fish of the present invention showing my new design.

FIG. 2 is a right side view of the tool for holding fish of the present invention showing my new design.

FIG. 3 is a left side view of the tool for holding fish of the present invention showing my new design.

FIG. 4 is a front view of the tool for holding fish of the present invention showing my new design.

FIG. 5 is a rear view of the tool for holding fish of the present invention showing my new design.

FIG. 6 is a top view of the tool for holding fish of the present invention showing my new design; and,

FIG. 7 is a bottom view of the tool for holding fish of the present invention showing my new design.

The broken lines are for illustrative purposes only and form no part of the claimed design.
